SHOE TREE

Frank A. Lisi, Philadelphia, Pa.

Application July 14, 1939, Serial No. 284,413

11 Claims. (Cl. 12—128)

This invention relates to shoe trees.

It is an object of this invention to provide a shoe tree of light, strong construction having originally a flat shape which may be refolded flat for convenient storage when not in use. Such a shoe tree is of particular advantage for traveling, particularly by airplane, where extreme lightness is of importance.

It is a further object of this invention to provide a shoe tree which will hold the toe portion of the shoe to the shape of the last without improperly distending or misshaping the proper contour thereof.

It is also an object of the invention to provide a shoe tree of open or skeleton form which will permit a free circulation of air into the shoe so that the latter will dry properly after wearing.

It is a further object of this invention to provide a shoe tree having relatively large flat surfaces for the reception of advertising material and the like.

Another object of the invention is to provide a shoe tree of sufficiently inexpensive material and construction so that the same may be given away by a shoemaker with each purchase of shoes, or may be provided for use of guests by hotels, transportation companies and the like.

Other objects and advantages of the invention will appear from the following description and the accompanying drawing, which illustrates one preferred embodiment of the invention.

In the drawing, Figure 1 is a view partly in side elevation and partly in vertical section of a lady's shoe with the shoe tree applied thereto.

Figure 2 is a transverse section taken on the line 2—2 of Figure 1 looking in the direction of the arrows.

Figure 3 is a perspective view of the shoe tree in the approximate shape assumed when placed in a shoe.

Figure 4 is a side elevation of the shoe tree in its flat condition, and

Figure 5 is a side elevation of a suggested container for dispensing pairs of shoe trees, the latter being indicated within the container by dotted lines.

For purposes of illustration the tree is shown as applied to a lady's shoe 10 having a sole 11 and an upper or vamp 12. It is to be understood, of course, that the tree may be applied to all types of boots and shoes. The tree proper comprises a blank of suitable sheet material bent or folded to proper shape, as shown generally at 15. The blank may be formed of somewhat flexible or resilient sheet material of stiffness sufficient

to provide the proper support for the shoe, but insufficient to prevent the bending of the flaps, to be described, to proper shape. For this purpose I have found numerous types of cardboard to be adequate and satisfactory, but of course it 5 will be understood that other material such as various light metals, corrugated boards, resin treated materials and the like may be employed. The tree 15 is normally substantially flat, and preferably comprises a pair of body portions 16 10 of substantially identical shape, each having bottom flaps 17 and upper flaps 18.

The bottom flap 17 is secured to, or bent from the body 16 along the line 19. The curved edge 22 of the flap 17 is preferably adapted, when the 15 flap is folded out of the plane of the body, to cover the insole 23 when the shoe tree is applied as shown in Figure 2. In order that the flap 17 may bend to conform to the shape of the insole, score lines 24 may be provided in the flap 17. 20

The upper flaps 18 are secured to, or folded from the body along the line 25 which is preferably curved inwardly in the central portion of the body portion 16. Provision of the curved line 25 insures that the tree will fit the contour of 25 the vamp 12 and further insures that the flaps 18 will bear upward against the vamp in a positive manner as the collapse of these flaps is prevented by the shape of the curve 25, which produces an arched effect, and ordinarily may 30 be as shown in Figure 4 with the line 25 curved. Thus ordinarily the shape of the curved fold 25 may be approximately as shown, but other forms of folds including straight folds have been found to be useful. Score lines 26 are preferably provided in the upper flaps 18 permitting the flaps to form themselves to the contour of the vamp and thus support the shoe in proper shape. The scoring in either upper or lower flaps is not sufficiently deep to weaken the tree so that while 40 the upper and lower flaps 17 and 18 form themselves somewhat to the shape of the shoe, they nevertheless offer adequate support and tend to keep the shoe in its proper shape.

While the body portions 16 may be used in two 45 separate pieces, it is preferable that these portions be secured together. Various means of securing them have been found to be adequate, but I have found it desirable to form the body portions integrally, joining them with a web 31 which 50 extends between the rear edges of the body portions and itself offers support to the tree and thus to the shoe. The web 31 preferably extends perpendicularly between the two body portions 16 when the tree is in position in the shoe and has 55

the further advantage of making the tree somewhat wider at the back so that the tree will fit the natural shape of the shoe somewhat better. I further prefer in order to insure that the shoe tree will assume the same shape each time it is applied to the shoe that the body portions 16 be joined intermediate their edges and to this end I may use the eyelet 27 or any other convenient fastening means. The body portions may be secured together adhesively over their entire surface or a portion thereof if desired.

5 The tree may be inserted into the shoe in the position shown in Figure 1 and the flaps will assume the position approximately illustrated in Figures 2 and 3, the flaps 18 tending to bear upwardly and the flaps 17 downwardly, thus supporting the shoe in its original and proper shape. The tree furthermore is held in this position by the centering of the lower end of the web 31 on 10 the insole of the shoe as particularly illustrated in Figure 1.

15 It will be seen particularly with reference to Figure 2 that rather than filling the entire inner portion of the shoe, the tree is of skeletal form and permits free circulation of air through the shoe thus aiding in drying thereof after wearing.

20 Pairs of the trees of my invention may be dispensed in their flat condition in numerous convenient forms such as the envelope-like covering 30 shown in Figure 5 which is represented to contain a pair of shoe trees. The body portion both 25 of the shoe trees and of the envelope may be decorated with suitable advertising material 33 which thus will make the tree a more attractive item from the standpoint of the dispenser and the consumer. If desired the envelope may be 35 made of transparent material such as "Cellophane," in which case the trees with the advertising thereon can be seen through the envelope 40 wall.

45 While I have illustrated and described in detail certain preferred forms of my invention, it is to be understood that changes may be made therein and the invention embodied in other structures. I do not, therefore, desire to limit myself to the 50 specific constructions illustrated, but intend to cover my invention broadly in whatever form its principles may be utilized.

55 I claim:

1. A shoe tree for insertion into a shoe comprising a flat body portion of non-metallic resilient sheet material having upper and lower flaps foldable out of the plane of the body into substantially the shape of the inside of a shoe.

55 2. A shoe tree for insertion in a shoe comprising a body portion, upper and lower flaps on said body portion, said flaps being foldable out of the plane of the body portion, at least one of said flaps being foldable from the body portion along a concave curved line.

60 3. A shoe tree for insertion in a shoe comprising a body portion having upper and lower flaps

foldable from the upper and lower portions of the body portion, said upper flaps forming substantially the shape of a vamp and said lower flaps forming substantially the shape of the front part of an insole.

5 4. A shoe tree comprising a doubled body portion, upper and lower flaps extending from said body, said upper flaps being adapted to be folded out of the plane of said body to assume the shape of a part of a vamp, said lower flaps being foldable out of the plane of the body assuming the shape of a part of an insole.

10 5. A shoe tree comprising a double fold of material forming a body, upper and lower flaps on said body, scored lines between said flaps and said body, and a plurality of lightly scored lines on said flaps, said upper flaps being adapted to conform to the shape of the inside of a vamp of a shoe and said lower flaps being adapted to conform to the shape of an insole.

15 6. A shoe tree for insertion into a shoe comprising substantially flat body portions joined at one edge thereof by an integral web and means carried by the upper and lower edges of the body portions for engaging the sole and the vamp of a shoe, and supporting said sole and said vamp in shape.

20 7. A shoe tree for insertion into a shoe comprising a flexible resilient vamp supporting portion, a sole engaging portion, and a substantially rigid body of small cross sectional area compared to the horizontal cross sectional area of the part of the shoe in which the shoe tree is to be inserted extending between the vamp and sole engaging portions and forming a strut for bracing them apart.

25 8. A shoe tree comprising a vertical body portion adapted to extend substantially from the sole to the vamp of the inside of a shoe, flexible resilient sole engaging flaps extending from either side of the bottom of said body portion and flexible resilient vamp engaging flaps extending from either side of the top of said body portion.

30 9. A shoe tree for insertion into a shoe comprising a substantially vertically extending body portion, sole engaging flaps extending from the base thereof and curved vamp engaging flaps extending from the top thereof.

35 10. A shoe tree comprising a single piece of stiff bendable sheet material folded upon itself to form 50 a normally vertical two-ply body, each of said body plies carrying an upper vamp engaging flap and a lower sole engaging flap.

40 11. A shoe tree for insertion into a shoe comprising a flexible resilient portion of sheet material adapted to fit inside of and support the vamp of a shoe, a sole engaging portion adapted to bear against the inner surface of the sole and a flat upright web constituting a strut bracing the 55 vamp and sole engaging portions apart.
